CLAIM

The ornamental design for a cleaning device with name plate, as shown and described.

DESCRIPTION

FIG. 1 is a top perspective view for the name plate of the cleaning device;

FIG. 2 is a bottom perspective view thereof;

FIG. 3 is a top view thereof;

FIG. 4 is a right side view, with the left side being a mirror image thereof;

FIG. 5 is a front view, with the rear being a mirror image thereof;

FIG. 6 is a top view of the cleaning device with the name plate removed;

FIG. 7 is a right side perspective view thereof;

FIG. 8 is a bottom view thereof;

FIG. 9 is a front view thereof;

FIG. 10 is a rear view thereof;

FIG. 11 is an enlarged top perspective view of the slot in the cleaning device which receives the name plate;

FIG. 12 is a top view of the cleaning device with name plate;

FIG. 13 is a right side perspective view thereof;

FIG. 14 is a bottom view thereof;

FIG. 15 is a front view thereof; and,

FIG. 16 is a rear view thereof.

The broken lines represent portions of the cleaning device that form no part of the claimed design.
